[57] CLAIM

The ornamental design for a bed, as shown and described.

DESCRIPTION

FIG. 1 is a front-side perspective view of a bed showing our new design;

FIG. 2 is a side elevational view thereof;

FIG. 3 is a front perspective view thereof, the dotted lines indicating environmental elements only;

FIG. 4 is a first partial perspective view of the lattice canopy design viewed from the bed looking up;

FIG. 5 is a second partial perspective view of the lattice canopy design viewed from the bed looking up;

FIG. 6 is a first partial perspective of the headboard section of our new design; and,

FIG. 7 is a second partial perspective of the headboard section of our new design.

The rear of the headboard and footboard are flat and unornamented.
